COMBINED CLOCK AND THERMOMETER

Paul Vogt, Les Hauts-Geneveys, Switzerland, assignor to
Derby SA, Neuchatel, Switzerland

Filed Nov. 27, 1968, Ser. No. 14,702

Claims priority, application Switzerland June 7, 1968

Term of patent 14 years

Int. Cl. D10—04

U.S. Cl. D42—7

FIGURE 1 is a front elevational view of a combined clock and thermometer embodying my new design;

FIGURE 2 is a reduced scale rear elevational view thereof;

FIGURE 3 is a reduced scale side elevational view thereof.

The side opposite that shown in FIGURE 3 is substantially a mirror image thereof.

I claim:

The ornamental design for a combined clock and thermometer, substantially as shown and described.
